UNITED STATES PATENT OFFICE

1,934,459

HIGH VACUUM FUSE

David C. Prince and Bertram Wellman, Schenectady, N. Y., assignors to General Electric Company, a corporation of New York

Original application March 23, 1928, Serial No. 264,113. Divided and this application July 22, 1929. Serial No. 379,976

4 Claims. (Cl. 200—120)

Our invention relates to fuses for interrupting electric circuits, and particularly to enclosed fuses of the direct-current type, comprising a combination of elements which cooperate in a way to secure new results by utilizing certain principles of electron emission in a very high vacuum.

A principal object of our invention is to provide a high-tension, high-vacuum fuse of the direct-current type which shall interrupt currents at high voltages without prolonged arcing and within a brief interval of time.

A further object is to provide a fuse which when it has blown leaves a gap of exceptionally high dielectric strength between the terminals of the fuse whereby there is no danger from subsequent breakdown across the gap.

A further object is the provision of fuse terminals composed of a refractory metal, which are so constructed that maintenance thereof at a temperature permitting thermionic emission of electrons, as when the fusible element is ruptured by predetermined flow of current, is precluded.

Among the advantages of our invention which are of great commercial importance are that the fuse reduces fire hazard to a minimum; is noiseless in operation; relatively small, relatively inexpensive, and quite definite in its action of interrupting the circuit when that current value for which the fuse is designed to operate is reached.

In accordance with our invention the fuse is maintained in a very high vacuum which not only protects the fuse metal from oxidation or other deteriorating influences but presents such definite conditions for loss of heat by conduction and radiation that the fuse operates with considerably greater uniformity at its designed current value.

Further in accordance with our invention, the fuse when connected in a direct-current circuit, functions to interrupt the current when the fuse blows by reason of rapid cooling of the cathode and consequent cessation of electron flow therefrom.

This application is a division of our co-pending application, Serial No. 264,113, filed March 23, 1928, for "High vacuum fuses."

Our invention will be more fully set forth in the following description referring to the accompanying drawing, and the features of novelty which characterize our invention will be pointed out with particularity in the claims annexed to and forming a part of this specification.

In the drawing, Fig. 1 represents a fuse em-

bodying our invention; Fig. 2 represents a modified form of fuse vessel; and Fig. 3 represents a modified construction of fuse embodying certain broad features of our invention together with certain improvements.

In Fig. 1 we have represented one example of a fuse embodying our invention. In this embodiment the vessel is indicated as made of vitreous material such as quartz or a suitable glass, examples of which are well known in the art of electron discharge devices, X-ray apparatus, and the like. As here shown the vessel is provided with a bulbous central portion 1. The fuse link 2 is located centrally of the bulbous portion and the ends of the fuse link are secured in any suitable manner to terminals 3 and 4 which are connected by the conductors 5 and 6 to terminal caps 7 and 8 respectively, which are indicated as extending over and secured in any suitable manner as, for example, by cement, to the neck portions of the vessel. The cylindrical portions of the caps 7 and 8 are adapted to be inserted in fuse-holding members or clips not illustrated.

The terminal members 3 and 4 of the direct-current fuse must be composed of a refractory metal having a high melting point, such as tungsten, for example, in order that there will be no cathode-spot effect, as hereinafter described. As is well known, a refractory metal, such as tungsten, is adapted when heated sufficiently to emit electrons thermionically, as contrasted with metals such as copper, silver, and nickel, which are of such low melting points that thermionic emission of electrons therefrom does not occur. The material of which the fuse link itself is made is not of the same importance, but tungsten is known to be a satisfactory metal and has the advantage that it can be raised to a very high temperature by passing the heating current therethrough while the vessel is being evacuated so that the fuse link is quite completely freed of occluded gases.

Where the fuse is to carry moderate values of current the leading-in conductors 5 and 6 may be sealed to the stems 9 and 10 of the vessel by a pinch seal. Examples of suitable leading-in conductors adapted to make a tight and permanent seal with glass are now well known in the art of incandescent lamps and high-vacuum devices. Such leading-in wires are described for example in Letters Patent to Fink No. 1,498,908, dated June 24, 1924. The ends of the stems 9 and 10 are provided with shields 11 and 12 to protect the seals against the injurious effect of electron bombardment during the operation of the

the fuse in interrupting a circuit as hereinafter described.

The shields 11 and 12, when disposed adjacent the terminals 3 and 4 of the fuse may likewise serve to aid in the dissipation of heat from the terminals by reason of the increased heat radiating surfaces of the shields. The shields may be of metal such as molybdenum since this metal has the advantage that when used in high-voltage, high-vacuum electron discharges it may be readily raised to a sufficiently high temperature by high frequency heating to drive out the occluded gases therefrom during exhaust.

The very best technique for securing an extremely high vacuum is important for securing the best results when the fuse operates. The vessel should be baked during exhaust to drive out occluded gases from the walls and all surfaces and metal parts within the vessel should be freed from occluded gases. It is preferable to de-gas metal parts such as the terminal members 3 and 4 and also the shields 11 and 12 before they are assembled in the vessel. As pointed out in Letters Patent to Langmuir No. 1,558,436, dated October 20, 1925, metal which has been freed from occluded gas does not readily reabsorb gas even though it is exposed to the air or other gases. This makes it possible thoroughly to de-gas such parts as desired before assembling in the vessel and facilitates the final operation of de-gassing and exhausting after assembly.

After the fuse elements have been assembled in the vessel sufficient current should be passed through the fuse to raise it to a temperature sufficient to drive out occluded gases while the exhausting operation is going on. The walls of the vessel should be thoroughly baked out and suitable means utilized, for example high-frequency heating, to assist in raising the metal parts in the vessel to a sufficiently high temperature to insure that after the vessel has been sealed off an extremely high vacuum will continue to be maintained although the fuse may become very hot when carrying currents approximating the value at which the fuse is designed to interrupt the circuit.

In the drawing, the projection 13 indicates one suitable place at which the vessel may be sealed off after the desired high vacuum has been produced. As indicated in the drawing, this location of the projection enables it to be covered by the metal fuse caps and protected from injury during handling of the fuse.

Experience with fuses of the high-vacuum type described will enable one to determine from the appearance of a fuse when a predetermined testing current is passed through it whether or not the vacuum is of the high order desired before the fuse is put into service on a line. If desired, however, any well known method of testing such a fuse may be employed to determine whether or not the vacuum is of the desired order.

In order better to understand the new functions and results of our invention, we will now describe the action which we believe explains why the fuse will interrupt a high-voltage circuit within a very brief interval of time and without the usual arcing or explosive defect attendant upon high-tension fuses of previous construction. At this point it should be borne in mind that there are two types of electron emission. Thermionic emission is produced by a heating of a metal to the point where the electrons in it have sufficient energy to break through the metal boundary into space. This emission phenomenon

is described by the Richardson Law, and is an important factor in the operation of our direct-current fuse. The second kind of electron emission we will call "cathode-spot emission." The theory which we believe to explain the last-named type of emission is set forth in detail in our co-pending application above referred to, and the following outline of the theory is believed to suffice for an understanding of the present invention.

In the event that terminals 3 and 4 are composed of a metal having a low melting point, such as copper, silver, or nickel, for example, rupture of the fusible element produces a very high potential gradient at that point of the cathode to which the fuse link was attached, whereby electrons are pulled out of the soft metal terminal at a temperature much lower than that corresponding to emission from a hot cathode of refractory metal such as tungsten. These electrons in turn collide with the vaporized metal in the space formerly occupied by the fusible element to ionize some of the metal vapor, thus producing additional electrons, the positive ions traveling to the cathode to accumulate there and maintain the high potential gradient necessary for continuing the flow of electrons, and also serving to maintain the cathode spot at high temperature by their constant bombardment. Accordingly, it is seen that the flow of electrons from the cathode, once it is started, continues as long as the conditions originally present obtain.

The flow of electrons by thermionic emission, however, necessitates that the cathode be heated to such temperature that electrons are emitted therefrom without regard to any cathode-spot effect. As previously stated, a refractory metal such as tungsten may be heated to such a temperature that thermionic emission therefrom occurs. However, when the temperature of the metal decreases to below this point electron emission practically immediately ceases. In other words, in order for thermionic emission from a metal such as tungsten to be started and maintained, the metal must not only be raised to the high temperature necessary to start such emission, but must be continuously maintained so. With the terminals 3 and 4 composed of a refractory metal, as tungsten, rupture of the fusible element 2, due to excessive current traversing the same, may momentarily cause the cathode to be heated sufficiently to emit electrons thermionically so that current will continue to flow but will tend to reduce in value as the gap across which the discharge is taking place increases. The terminals, and particularly the cathode, should be so constructed that the heat due to rupture of the fusible element may be rapidly conducted away and dissipated, and they should therefore preferably be of reasonably large size unless special cooling means are provided.

It is difficult to secure sufficient metal vapor from the tungsten cathode to maintain a cathode spot. Several hundred amperes at 250 volts have been tried and found insufficient where tungsten contacts are separated in a high vacuum. With direct current flowing, the cathode will continuously be cooled by the emission of electrons and by conduction through and radiation from the metal until the temperature is too low to emit further electrons thermionically after which the circuit will be opened. The small amount of vapor produced from the tungsten cathode is not sufficient to result in a positive ion bombardment of the cathode sufficient to restore as much heat

as is conducted away from a properly designed cathode. The thermionic electron emission of course bombards the anode while the current is flowing and raises the anode to a high temperature but when the circuit is interrupted the anode cools down. Such tungsten fuse terminals are not well adapted for operation to interrupt alternating current because of the fact that the electron bombardment from the cathode to the tungsten anode raises the anode to such a high temperature that it is in a condition to emit electrons thermionically to restart the discharge when the alternating-current wave reverses so as to make the fuse terminal which formerly was the anode now the cathode. The heating of the anodes from electron bombardment is so effective that the current flow may be maintained in an alternating-current circuit after the fuse has blown by reason of the alternating heating of the electrodes and the hot cathode electron emission occurring alternately from one fuse terminal and then the other.

The cessation of electron flow and consequently the flow of current from the tungsten cathode after it has cooled to a point below which thermionic emission cannot take place, is accompanied by comparatively small dissipation of energy. Oscillograms have shown that the arc voltage across the terminals is low as compared with the line voltage until it rises rapidly to a value such as to cause interruption of the current; moreover, the duration of the current flow after the fusible element has blown is brief concurrent with rapid decrease in magnitude of the current.

Since the amount of energy that must be dissipated after the fuse link is broken is so small, the usual tremendous explosive effects are absent and a relatively small vessel is adequate for a fuse of considerable voltage and capacity. When the fuse blows it merely glows brightly for a moment. Its operation is entirely without noise since there is no air in the vessel to transmit sound waves.

In determining the size of the fuse vessel there are two requirements which must be met. First the size of the vessel should be large enough so that no part of the fuse link before or during blowing can come into contact with the glass walls. If such contact should occur it may impair the vacuum without breaking the envelope because the hot metal will cause the glass to evolve gas. Or the wall may be cracked by the hot wire or the wall may be punctured due to high potential gradients in the glass due to the wire point against it. In any event the vacuum is impaired and its dielectric strength lost.

The distance between the fuse terminals 3 and 4 can be made relatively small so that a relatively short fuse link can be used. This reduces the amount of gas and metal vapor which may be evolved when the fuse blows and simplifies the problem of preventing contact between the fuse and the wall of the vessel. A gap between electrodes of the order of $\frac{1}{8}$ of an inch in air will break down at approximately 30,000 volts. As the pressure is reduced below atmospheric pressure the voltage required to break down the gap is at first decreased until it reaches a minimum of from 100 to 200 volts at a pressure of a few microns (millionths of a meter). As the pressure is reduced still further the voltage necessary to break down the gap steadily rises until values of the order of millions of volts per centimeter potential gradient are required in approximately perfect vacuum. It is thus necessary for a vacuum fuse to have a vacuum which is more perfect than

a small fraction of a micron for any commercial voltage and the excellence of the fuse improves as the vacuum is made better and better. A vacuum which will remain of the order of .01 or .001 of a micron is satisfactory but as above indicated an extremely high vacuum is important and should remain high after the fuse has blown.

Tests have shown that fuses may be built to interrupt several amperes at 15,000 volts without making the fuse vessel of large size and yet maintain such a high vacuum that the gap may not be subsequently broken down with testing potentials of the order of a 100,000 volts. There is undoubtedly a volume below which it is inadvisable to go for the vessel of a successful fuse for a given capacity and voltage on account of the evolution of small amounts of gas when the fuse link blows. These amounts of gas are too small to raise the pressure enough to cause failure in vessels of rather small size. The metallic vapor of the fuse itself condenses practically instantaneously upon rupture thereof, and so does not impair the vacuum to any material extent.

Using a tubular glass vessel two inches in diameter and a fuse link of the order of $1\frac{1}{2}$ inches in length we have successfully interrupted 45 amperes at 15,000 volts D.C. The fuse vessel could probably be made still smaller for such service, but the example given conveys a fair idea of the size of the vessel required for lower voltages.

For fuses of large capacity and moderate voltage it may be desirable to use a metal vessel instead of a glass vessel. The technique of making proper seals with metal vessels is now known to those skilled in the art. Examples of such seals are shown in Letters Patent to Kruh et al., No. 1,564,690, dated December 8, 1925, and to House-keeper No. 1,294,466, dated February 18, 1919. For the extremely high-voltage circuits there will not be the same advantage in using a metal vessel because of the fact that the size of the device is limited by the creeping and striking distance of the circuit voltage along the outside and a metal vessel being a conductor will be disadvantageous in this respect.

Suitable remotely controlled or manually operated disconnecting switches may be provided for opening the circuit at points each side of the fuse after it has blown so that a new fuse may be inserted. The operation of the fuse is so successful and it is so much less expensive than an adequate oil switch that we anticipate that our high-vacuum fuses will have a considerable field of use as a substitute for such switches. Automatically operating mechanism may be provided to substitute another fuse in the circuit when one fuse has blown. The fuse may also be used as a safety device in series with an oil switch which normally controls the circuit, the fuse operating whenever the switch fails to open the circuit.

Referring to Fig. 2 a modified form of fuse vessel is indicated, the vessel being cylindrical throughout. The diameter of the vessel will be made adequate and the principles which govern this will be obvious to those skilled in the art from the foregoing discussion. The terminal caps have not been illustrated in this figure but it will be understood that an arrangement like that of Fig. 1 is suitable.

In Fig. 3 a high vacuum fuse embodying the broad principles of our invention is disclosed together with a further improvement which facilitates the process of freeing the fuse-supporting terminals from occluded gases. As shown in this

figure the fuse-supporting terminals 22 and 23 are made in the form of hairpinlike loops. For direct-current service these loops are made of a refractory metal having a high melting point, such as tungsten for example, and the final operation of depriving the loop terminals of occluded gas is facilitated by the fact that a local heating current may be passed through each of the loops by connecting the leading-in wires for the respective loops to suitable sources of current. Currents can thus be utilized which are as large as necessary without dependence upon the amount of current the fuse link itself can carry. Loops of considerable size can thereby be readily brought to the temperature necessary to free them from occluded gases while the final exhausting operation is taking place and the necessary current can also be passed from a suitable source of current through the fuse link so as to bring it also to the desired high temperature. The arrangement shown in Fig. 3 is disclosed and claimed in the co-pending application of David C. Prince, Serial No. 264,117, filed concurrently herewith and assigned to the same assignee as the present application.

While we have illustrated certain embodiments of our invention and described its theory of operation as we understand it, and described certain relations of utility for our invention, it is to be understood that we are not bound by any theory of operation, and it is moreover apparent that modifications and changes will occur to those skilled in the art without departing from our invention, and it is contemplated that our fuse may find a greater field or use in some application other than we have described and we therefore aim in the appended claims to cover all modifications and applications within the true spirit and scope of our invention.

What we claim as new and desire to secure by Letters Patent of the United States, is:

1. A high vacuum direct current fuse comprising an evacuated vessel, terminals located within said vessel, and a fusible element connected to

45

and interposed between said terminals, all of the elements within the vessel as well as the walls of the vessel being thoroughly freed of occluded gas, said terminals being relatively large with respect to the fusible element and at least one of the said terminals being composed of a refractory metal whereby said terminal tends to cool when operating as a cathode and thereby to reduce electron emission therefrom and stop the flow of current. 80 85

2. A direct-current fuse of the high vacuum type comprising a sealed vessel having a vacuum of the order of about one-thousandth of a micron, spaced terminal members within said vessel composed of a metal having a high melting point, said metal being capable of thermionic electron emission, and a fusible element interconnecting said terminal members. 90 95

3. A direct-current fuse of the high vacuum type comprising a sealed vessel having a vacuum of the order of about one-thousandth of a micron, spaced terminal members composed of tungsten disposed within said vessel, and a fusible element interconnecting said terminal members, said terminal members having comparatively large heat-dissipating surfaces with reference to the current traversing the terminals during rupture of the fusible element for rapidly cooling said members. 100

4. A direct-current fuse of the high vacuum type comprising a sealed vessel having a vacuum approximately of the order of from .01 to .001 micron, spaced terminal members composed of tungsten disposed within said vessel, and a fusible element connected between said terminal members, the cathode terminal member having a comparatively large heat-radiating surface with reference to the current traversing the same during rupture of the fusible element, whereby continued thermionic emission from the cathode is prevented. 105 110 115 120
